CRACKING HYDROCARBON OIL

Sijbren Tijmstra, Berkeley, Calif., assignor to
Shell Development Company, San Francisco,
Calif., a corporation of Delaware

Application March 20, 1936, Serial No. 69,791

3 Claims. (Cl. 196—50)

This invention relates to a process of cracking hydrocarbon oils, consisting in the conversion of heavier hydrocarbons into lighter hydrocarbons, usually of gasoline or similar boiling ranges, the conversion being effected by heat, and usually under superatmospheric pressure. Particularly, my invention relates to improvements in such processes whereby the formation of coke and similar objectionable carbonaceous materials in the cracking coils and other parts of the apparatus is to the large extent prevented.

Cracking operations, as usually carried out, are attended with the formation of large amounts of undesirable carbonaceous materials, such as coke, tar, and other highly polymerized hydrocarbons, along with the gasoline and similar fractions. Besides constituting a waste of hydrocarbons, the formation of these materials is objectionable because it causes the overheating of the cracking coils; it has heretofore been attempted to reduce the formation of such substances by a judicious choice of operating conditions, or by subjecting the initial hydrocarbon mixture to a preliminary refining treatment, as by removing asphaltic materials from the stock charged to the cracking coils.

I have found that the removal of asphaltic substances, such as asphaltenes, from charging or recycle stock in the usual way, as by precipitation of solid matter with propane or similar hydrocarbons, does not effectively reduce the formation of the objectionable carbonaceous materials, but that a material improvement is achieved by subjecting the hydrocarbon oil to be fed to the cracking coils to the precipitating action of low molecular hydrocarbons, particularly aliphatic hydrocarbons of less than seven carbon atoms in the molecule and, preferably, the so-called permanent gases of less than four carbon atoms, under a high pressure, and at a temperature near to or above the critical temperature of the gases, whereby the oil is caused to separate into two liquid phases of different specific gravities. One particular form of the treatment consists of producing separable non-gaseous phases by mixing the cracked material with a gaseous treating agent under temperature and pressure conditions which are less intense than its critical condition but which are insufficient to cause the condensation of the treating agent. The heavier liquid phase (which may often be extremely viscous, or semi-solid) is separated from the lighter liquid phase, and the latter is utilized as the charging stock to the cracking coil, or as a source for the cracking

stock. The pressure of the treatment is normally between about 20 and 200 atmospheres pressure, there being sufficient low-boiling gas in the treating vessel to cause the normally liquid hydrocarbons to be substantially saturated with the gaseous hydrocarbons. This treatment may be applied to the cracked residue withdrawn from the cracking furnace, or to the initial feed oil, or to both, separately or in admixture. While the present invention is especially useful in connection with liquid phase cracking processes, it may also be applied to the treatment of cracked products resulting from a vapor phase cracking process.

My invention will be described with reference to the accompanying drawings, in which Figures 1 and 2 are schematic flow diagrams illustrating schematically the arrangement of the apparatus suitable for carrying out the invention, it being understood that the invention may be operated in many other types of apparatus, and under conditions other than those particularly described, without departing from the spirit and scope of the invention. While a simple form of cracking unit has been illustrated, any other form may be substituted therefor; and since the operation of such units is well understood in the art, the following specification will describe in detail only the particular improvements constituting the present invention.

Referring to Figure 1, 1 represents a furnace provided with suitable heating coils and burners. A charging stock, consisting of uncracked stock and recycle stock, is fed to the furnace 1 through a conduit 2, although the uncracked stock and recycle stocks may in certain cases be cracked separately. The cracked products may be withdrawn from the furnace at 3, and fed directly to a transfer line 4 through a valve 5. If desired, the valve 5 may be closed, and the valve 6 opened, thereby flowing the cracked materials through a reaction zone 7, from which cracked stock may be withdrawn at 8. The rate of reaction may be controlled by introducing a cooling medium, such as a cooled gas obtained in the stabilizer unit, or a portion of the raw feed from the tank 9, through a conduit 10; or by quenching the material in the line 4 by introducing the cooling medium through a valve 11.

The cracked materials, instead of being fed into the usual vaporizing unit, in which the pressure is usually reduced and the vaporizable material separated from the cracked residue, are, according to my process, treated with a low molecular gaseous treating agent at a high pressure 55

to effect a different type of separation. The cracked products may be treated either alone, or together with the raw feed. According to one mode of treatment, the mixture is fed through 5 a throttle valve 15 to a multiple outlet valve 16, constructed to divert the flow of cracked material to one of several settling tanks 17, and 18, it being understood that any number of these tanks 10 may be provided. If desired, the cracked products may flow to an indirect heat exchanger to cool prior to their introduction into the tank 17. When the tank 17 has been partially filled with cracked materials, the flow is diverted to the tank 18 and a low-molecular gas from the tank 19 15 is fed through the valves 20 and 20a to the bottom of tank 17, thereby bubbling through the mixture and coming into intimate contact with the latter. The gas is introduced under a pressure to cause a substantial amount of the cracked 20 material to be condensed, or to remain in the liquid state. For example, all components of the mixture boiling above about the boiling temperature of aliphatic hydrocarbons having between about three to six carbon atoms may be 25 liquid, although it is also possible to select temperatures and pressures at which the greater portion of the gasoline hydrocarbons are vaporized, and only higher boiling hydrocarbons are in the liquid state.

30 The gas is introduced until the proper pressure is established, and a sufficient quantity of gas at a para-critical temperature is dissolved in the liquid to cause the latter to separate into two liquid phases. The separation of the liquid material into two liquid phases is occasioned by the 35 lowering of the density of the liquid oil in the tank 17 caused by the introduction of the gas, and it should be noted that enough space must be left in the tank 17 prior to the introduction 40 of the gas to allow room for this expansion.

45 While I have shown the addition of low boiling hydrocarbons to the tank 17, it should be noted that the cracked materials in the transfer line 4 already contain substantial amounts of these low boiling hydrocarbons of less than seven carbon atoms, and that in certain cracking operations, the addition of hydrocarbons from the tank 19 is not necessary. This is particularly true when the phase separation occurs at higher temperatures, e. g., at above about 150° C., because at 50 this temperature more of the hydrocarbons in the cracked mixture are in a para-critical state, and effective to cause the separation of the heavy hydrocarbon mixture into two liquid phases. In 55 this case it is only necessary to increase the pressure on the system to cause these gases to be dissolved in the liquid oil, thereby lowering the density of the latter and causing a separation into two liquid phases.

60 The temperature in the settling tank of phase separator 17 must be high enough to cause the low-boiling hydrocarbons which are active in causing the formation of the liquid phases to be in the para-critical state. A substance is said to be in its para-critical state when it is above, at, or slightly below its critical temperature, the lower limit being about 40° C. below the critical 65 temperature. Since the mixture in the transfer line 4 contains a great diversity of hydrocarbons 70 of varying molecular sizes and critical temperatures, it will be noted that when the temperature in the chamber 17 is comparatively low, fewer of these hydrocarbons will be in the para-critical state than if higher temperatures are employed, and it becomes necessary to add more low-boiling 75

hydrocarbons from the tank 19, in order to have a sufficient concentration of active low-molecular hydrocarbons in the mixture to cause the formation of two liquid phases. When the low-boiling hydrocarbons consist mainly of methane and ethane, temperatures as low as 0° C. and lower are operative, although these low temperatures would, for practical reasons, rarely be employed. The higher boiling hydrocarbons, such as pentane and hexane, are less desirable and with many 10 types of hydrocarbon oils it is difficult to cause the formation of two liquid phases with these hydrocarbons because, when used alone, they necessitate the use of high temperatures, generally above 200° C., and because such high temperatures 15 promote miscibility, thereby preventing the formation of two liquid phases. The presence of such hydrocarbons which have slightly higher molecular weights than the hydrocarbons in the para-critical state and which are present in the 20 system in the liquid state under the conditions of the treatment is, however, beneficial, since they promote the solubility of the active hydrocarbons, and aid in lowering the density of the mixture 25 being treated.

The temperature should always be well below the critical temperature of the composite mixture introduced into the separator 17 and, in general, I prefer to operate the phase separator at a temperature between about 20° C. and 30 250° C., and at a pressure between about 20 and 200 atmospheres. When raw stock has been introduced through the line 10, the resulting mixture of gas and stock fed into the tank 17 will often have the desired temperature; if not, the 30 mixture may be cooled by introducing raw stock into the tank 17 through a valve 21, or by flowing the raw stock through a valve 22 and cooling coil 23. Alternately, the mixture may be passed through a heat-exchanger before introduction 35 into the tank 17.

40 As a result of the formation of two liquid phases by the above described method, the mixture will be separated into two portions: most of the low-boiling hydrocarbons which are in the para- 45 critical state, and other low-boiling hydrocarbons, such as gasoline, and the like, as well as heavier hydrocarbons which are suitable for use as charging stock to the cracking unit, are concentrated in the lighter liquid phase, or are present in a gas phase above the liquid phase; and the heavier phase will consist mainly of heavy hydrocarbons which are largely responsible for the 50 formation of coke in the cracking unit.

55 The lighter and heavier liquid phases from the separator 17 are separately withdrawn, by withdrawing the liquid material through valves 24 and 25, the latter valve being set to direct the flow to the conduit 26 until all of the heavier phase has been withdrawn, whereupon the valve 60 25 is set to divert the flow of the lighter phase to the conduit 27. The light and heavy phases are then fed to the expanding vessels 28 and 29, respectively, where the permanent gases or other 65 highly volatile gases are separated under a reduced pressure, the gases being conducted to the tank 19 through conduits 30 and 31, respectively, or removed from the process.

70 The residual gases in the tank 17 may be returned to the tank 19 through the low pressure line 32 by opening the valve 33. If, however, the tank 17 is operated under a pressure low enough to vaporize a substantial portion of gasoline and other desirable hydrocarbons, these may be re- 75

covered by flowing the gas through a valve 34 to the stabilizer unit, subsequently described.

After the tank 17 has been emptied, the flow of cracked material from the still is again diverted 5 to the tank 17, and the material accumulated in the tank 18 is treated in the manner described above for the tank 17, corresponding apparatus being indicated by primed numerals.

The liquid hydrocarbons from the expansion 10 vessel 28 are fractionated in the fractionating column 35, which may be operated at any suitable temperature and pressure to produce a bottom product at 36 containing hydrocarbons of boiling temperature ranges suitable for use as 15 the cracking stock, and an overhead product at 37, containing the lower boiling liquid hydrocarbons and gaseous hydrocarbons which were not separated in the expansion vessel 28. All or a portion of the overhead product from 37 is condensed in a condenser 38, and recycled as reflux, 20 the portion which is not recycled being further treated in a stabilizer column 39, for the separation of additional quantities of gases, which may be introduced into the tank 19 through a conduit 25 40 or withdrawn at 41. The stabilized bottom product from the column 39 may be withdrawn at 42 and stored in tank 43.

The fractionating column may be operated in any desired manner, as is well known in the art. 30 Heat may be supplied to this column by withdrawing light gases from the reaction chamber 7 through a conduit 48; or incondensable or other light hydrocarbons may be sent through the cooling coils 23, 23' instead of the raw feed, and the 35 heated hydrocarbons may be fed to the bottom of the tower 35 as shown in Figure 2. The raw feed may, if desired, be introduced into the column 35 through a conduit 50, either after passing through heat exchangers 23, 23', or through 40 the valve 51.

The bottoms from the expansion vessel 29, withdrawn at 44, normally consist of highly viscous aromatic oils often containing large amounts of asphaltic and resinous materials, and may be 45 disposed of in any desired manner. When the lower phase in the separator 17 contains appreciable quantities of hydrocarbons of gasoline and similar boiling temperature ranges, it may be desirable to fractionate the bottoms from the vessel 29 in a steaming column 45, and return the 50 more volatile constituents to the fractionating column 35, or to the stabilizer 39 through a conduit 46, the viscous aromatic and other undesirable materials being withdrawn at 47.

The vessels 28 and 29, and the stabilizer unit 55 39 are operated to accumulate in the tank 19 only gases having molecular weights less than 80, and preferably less than 50. These hydrocarbons may be of the saturated paraffinic or of the olefinic type. If desired, these gases may be desulfurized in the desulfurizing apparatus 12 by closing the valve 13 and opening the valve 14. This treatment may, for example, comprise the step of washing the gas with a solution of potassium phosphate, or some other alkaline absorbing agent, capable of removing hydrogen sulfide. Mercaptans may also be removed from the gas in this treatment. The quantity of the gaseous hydrocarbons supplied from the tank 19 60 to the tank 17 or 18 depends upon the quantity of similar gases which are present in the cracked materials in the transfer line 4. I prefer to add a sufficient quantity of gas from the tank 19 to maintain a gas phase in the separator 17 in 65 equilibrium with the two liquid phases. The

presence of a gas phase is, of course, not essential, but is preferred for the purpose of insuring that a sufficient quantity of gas is present in the system to saturate the liquid hydrocarbons at the prevailing pressure. It should, moreover, be noted that while I prefer to saturate the liquid hydrocarbons with the gas, this is not always necessary, since the formation of two liquid phases is possible even though lesser amounts of gas are employed. This is true particularly when 10 higher temperatures, in the vicinity of 100-250° C. are employed.

As a modification of the above process, I may introduce all or part of the low-boiling hydrocarbons from the tank 19 through the valve 28' and 15 digest the cracked oil in the reactor 7 in the presence of the added low-boiling hydrocarbons. This is often effective to prevent the clogging of conduit lines between the furnace and the tanks 17 and 18.

It is also possible to operate the process with a single separating tank, by flowing the cracked products, together with the gaseous treating agent, and, if desired, together with the raw feed, into a continuous liquid phase separator at the 20 necessary pressure and temperature. The pressure in the cracking coils may at times be sufficient for this purpose, but in most processes it is necessary to increase the pressure by means of a pump.

As was indicated above, the raw feed stock may be similarly subjected to the treatment described above in connection with the tanks 17 and 18, in the absence of the cracked materials. The treated feed stock may then be fed either directly to the cracking coils or into the fractionating column 35.

While I have in the foregoing specification particularly described the use of gaseous hydrocarbons for causing the formation of the non-gaseous phases in the tanks 17 and 18, because these gases are most conveniently available in cracking plants it should be noted that other low-molecular gaseous substances having low critical temperatures, preferably below 250° C. 45 may also be employed. Examples of such gaseous treating agents are: sulfur dioxide, carbon dioxide, carbon monoxide, methyl fluoride, hydrogen, etc.

Figure 2 illustrates a modified flow diagram of 50 the process, similar reference characters designating the same elements as in Figure 1. According to this modified arrangement, the incondensable gases from the tank 19 are passed through the coils 23 and 23' to regulate the temperature 55 of the cracked products in the tanks 17 and 18. The heated gases are then fed into the bottom of the fractionating column 35 via conduits 50 and 48, either in addition to or in lieu of the 60 gases withdrawn from the reactor 7 via valve 49, to supply heat to the column.

While in Figure 2 certain alternate arrangements and conduits have been omitted, it should be understood that any or all of the modifications described heretofore in connection with 65 Figure 1 may also be applied to the process shown in Figure 2. Thus, the raw feed from the tank 9 may be introduced either directly into the cracking furnace via conduit 10 as shown in Figure 2, or it may be passed through the settling tanks 70 or the fractionator.

I claim as my invention:

1. In a process for converting heavy hydrocarbons into lighter oils, comprising the steps of subjecting the heavy oil to pyrogenous cracking 75

conditions, subjecting the cracked oil containing a substantial portion of the gasoline components and heavier components in a separating zone to the precipitating action of a quantity of low molecular hydrocarbons having less than four carbon atoms at a separating temperature at which said low molecular hydrocarbon is in the para-critical state, at a pressure at which said gasoline components and heavier components are reduced to the liquid state and at which a sufficient quantity of said low molecular hydrocarbons are dissolved in the liquid cracked oil to cause the formation of two liquid phases having different specific gravities, separating said liquid phases, fractionating hydrocarbons contained in the separated lighter phase in a fractionating

zone, the improvement consisting of heat-interchanging the cracked hot oil with an incondensable hydrocarbon gas in said separating zone, thereby heating the gas and cooling the oil to the separating temperature, passing the heated gas into said fractionating zone as a heating medium therefor, separating a heavy hydrocarbon fraction from the fractionating zone, and subjecting said heavy fraction to cracking. 5

2. The process according to claim 1 in which the separating temperature is above 150° C. 10

3. The process according to claim 1 in which the separating temperature is above the critical temperature of the low molecular hydrocarbon. 15

SIJBRON TIJMSTRA.
